UNITED STATES PATENT OFFICE

131,789

DESIGN FOR A TEXTILE FABRIC

Annette Boutemy, New York, N. Y.

Application February 19, 1942, Serial No. 105,905

Term of patent 3½ years

To all whom it may concern:

Be it known that I, Annette Boutemy, a citizen of France, residing in New York city, county of New York, and State of New York, have invented a new, original, and ornamental Design for a Textile Fabric, of which the following is a specification, reference being had to the accompanying drawing, forming part thereof.

The figure on the drawing is a plan view of a textile fabric showing my new design. The design unit is contained between the dot and dash lines, which unit is repeated in regular succession as indicated by the extensions beyond the unit boundaries.

I claim:

The ornamental design for a textile fabric, substantially as shown and described.

ANNETTE BOUTEMY.
